UNITED STATES PATENT OFFICE

155,370

DESIGN FOR A PORTABLE GOLF PUTTING CUP OR SIMILAR ARTICLE

Robert E. Watkins, deceased, late of Kansas City, Mo., by Myrtle V. Watkins, executrix, Kansas City, Mo., assignor to Myrtle V. Watkins, Kansas City, Mo.

Application August 11, 1947, Serial No. 140,818

Term of patent 7 years

(Cl. D34—5)

To all whom it may concern:

Be it known that Robert E. Watkins, late a citizen of the United States, residing at Kansas City, in the county of Jackson and State of Missouri, deceased, invented a new, original, and ornamental Design for Portable Golf Putting Cup or Similar Article, of which the following is the specification, reference being had to the accompanying drawing, forming part thereof.

Fig. 1 is a front elevational view of a portable golf putting cup or similar article, showing his new design.

Fig. 2 is a perspective view taken partly from the rear of the device.

Fig. 3 is a side elevational view of the device.

What is claimed is:

The ornamental design for a portable golf putting cup or similar article, substantially as shown.

MYRTLE V. WATKINS,
Executrix of the Estate of Robert E. Watkins,
Deceased.
